UNITED STATES PATENT OFFICE.

LOUIS C. NICHOLS, OF MILWAUKEE, WISCONSIN, ASSIGNOR, BY MESNE ASSIGNMENTS,
TO ALLIS-CHALMERS MANUFACTURING COMPANY, A CORPORATION OF DELAWARE.

TRANSFORMER.

1,143,305.

Specification of Letters Patent. Patented June 15, 1915.

Application filed April 8, 1911. Serial No. 619,669.

To all whom it may concern:

Be it known that I, Louis C. Nichols, a citizen of the United States, residing at Milwaukee, in the county of Milwaukee and State of Wisconsin, have invented certain new and useful Improvements in Transformers, of which the following is a full, clear, and exact specification.

My invention relates to transformers, and particularly to those provided with coils spaced apart to permit the circulation of the cooling fluid.

Heretofore in the construction of transformers, the spacing strips or rods which have spaced apart the different sections of the transformer windings for cooling purposes have been straight. Since these strips are parallel to certain parts of the individual wires forming the transformer windings, as for instance to those parts which pass through the openings in the two-part iron core customarily used in transformer construction, this leaves most of such wires not directly supported or braced by the spacing strips. These wires have to rely for their bracing upon the insulation surrounding them. Under normal conditions this is usually sufficient. However, in case of a short circuit, or even a heavy overload, on the transformer, the stresses which are set up are greater than the unsupported insulation can bear, in which case the coils may be disrupted.

It is the object of my present invention to provide for bracing all the wires of the different sections of the transformer winding, while still allowing the free passage of a cooling fluid through spaces between such sections. In attaining this object the spacing strips, sticks, or rods which usually extend in the general direction of the wires of the transformer windings are made otherwise than straight, so that they will extend across a number of wires. The strips are preferably made in a zig-zag or undulate form, though this precise shape is not necessary. A number of strips are used, being so spaced apart that among them they brace all the wires forming the winding. The spaces between the several strips are open for the passage of the cooling fluid, which may be anything desired, such as oil or air.

The various novel features of my invention will appear from the description and

drawings and will be particularly pointed out in the claims.

Figure 1 is a section substantially on the line 1—1 of Fig. 2, and illustrates my invention as applied to an oil-filled, water-cooled transformer; and, Fig. 2 is a section substantially on the line 2—2 of Fig. 1, the windings being shown in elevation for the sake of simplicity.

The transformer consists primarily of the laminated core 10 and the windings 11, the two sides of the latter passing through openings in the two parts of the former, so that the core and windings are interlinked. The windings 11 are formed in a number of sections, preferably separated by barriers 12, these latter being spaced from the coil sections 11 by spacing sticks, strips, or rods 13 and 14. These rods are preferably made of some insulating material, such as fuller-board. The spacing strips 14 are short and straight, extending transversely to the wires forming the heads of the windings. The strips 13, which are here shown as extending the full length of the winding through the openings in the core 10 and in the general direction of the wires forming the sides of the transformer winding, are not straight, being preferably of a zig-zag, undulate, or serpentine form, as illustrated. The shape of the sticks 13 need not be precisely as illustrated, but may be varied widely. Each strip extends back and forth across a number of wires of the winding. The strips 13 are so spaced that no wires of the winding are left unsupported, each strip 13 extending across a group of wires which is contiguous with the group of wires covered by the adjacent strip 13. In order to show how the spacing strips overlap the different wires of the winding, part of the insulation between the strips and such wires is broken away in Fig. 1. The strips 13 offer substantially no more resistance to the passage of a cooling fluid through the spaces on each side of the winding sections 11 than would straight strips such as formerly used, and in addition firmly brace each individual wire of the winding.

My invention is applicable to any style of transformer. By way of example, I have shown it as applied to a transformer of the oil-filled, water-cooled type. The transformer is contained in an oil tight tank 15

mounted on a base 16. The tank is filled with oil, which is cooled and kept in circulation through and around the transformer by a flow of water through a coil of pipes 17 near the top of the tank 15. Since this feature forms no part of my present invention it requires no detailed explanation here.

What I claim as new is:

1. In electrical apparatus, a plurality of 10 sections of winding, and means for spacing said winding sections apart comprising spacing elements extending in the general direction of the adjacent individual turns of one of said spaced sections and spaced apart and 15 bent in a plane parallel to the adjacent side of said latter winding section, each of said elements forming a bearing for a plurality of adjacent individual turns of said latter winding section at a plurality of spaced 20 points.
2. In a transformer, a core provided with an opening, a winding extending through such opening, said winding being formed of spaced sections, and strips crooked in a plane 25 parallel to an adjacent side of one of said sections for holding said sections apart, each strip overlapping and forming a bearing for adjacent turns of a section at spaced points thereof.
3. In a transformer, a core, a plurality of 30 separately formed sections of winding thereon, and a spacing element between adjacent winding sections, said element extending in the general direction of the adjacent turns 35 of the spaced winding sections and being zig-zag or undulate in cross-section in a plane parallel to the adjacent sides of the spaced sections.
4. In a transformer, a core, a winding 40 thereon in a plurality of sections, and spacing strips between adjacent sections, said strips being laid in the same general direction as the adjacent portions of the individual turns of said spaced sections and being 45 of such cross-sectional shape in a plane parallel to the adjacent sides of the spaced sections as to bear against a number of adjacent individual turns whose width is greater than the width of said strips at any point thereof.
5. In a transformer, a core, a plurality of 50 separately formed winding sections thereon, the adjacent sides of adjacent winding sections being approximately parallel, and spaced elements between adjacent winding 55 sections and extending in the same general direction as the adjacent portions of the in-

dividual turns of the winding sections and forming a bearing for all the individual turns of the adjacent layers of said winding sections at spaced points.

60

6. In a transformer, a core, a winding in a plurality of sections mounted on said core, said sections being in the form of coils having faces at right angles to the axis of the core, and means for spacing adjacent coils 65 apart comprising spacing strips zig-zag or undulate in cross-section in a plane parallel to the adjacent sides of the spaced coils.

65

7. In a transformer, a core, windings associated therewith and divided into sections, 70 and spacing strips between adjacent sections, said strips being bent in a plane parallel to the adjacent sides of the spaced sections, and the edges of each strip extending across a plurality of adjacent turns of each of two 75 adjacent sections of said windings for spacing said sections apart.

70

8. In a transformer, a core, a winding associated therewith and divided into sections, 80 and spacing strips between adjacent sections, adjacent spacing strips between two sections being separated by a distance greater than the thickness of an individual turn of the winding, and said spacing strips being bent in a plane parallel to the adjacent sides of 85 adjacent sections and overlapping each turn of said winding to effectively space the turns of one section of winding from those of an adjacent section.

80

9. In electrical apparatus, a core, a plurality of sections of winding thereon, and means for spacing said winding sections apart comprising an element bent in a plane 90 parallel to the adjacent side of one of said winding sections and forming a bearing for 95 a plurality of turns of said latter winding section at a plurality of spaced points.

90

10. In a transformer, a core, a winding in a plurality of sections mounted on said core, 100 said sections being in the form of coils whose axes are substantially parallel to the axis of said core, and means for spacing adjacent coils apart comprising spacing strips zigzag or bent in a plane parallel to the adjacent side of one of said coils.

105

Milwaukee, Wis., April 5, 1911.

In testimony whereof I affix my signature, in the presence of two witnesses.

LOUIS C. NICHOLS.
